UNITED STATES PATENT OFFICE.

**ARTHUR M. STANLEY, OF LYNN, MASSACHUSETTS, ASSIGNOR TO STANLEY STEEL
WELDED WHEEL CORPORATION, OF BOSTON, MASSACHUSETTS, A CORPORATION
OF DELAWARE.**

DESIGN FOR A VEHICLE-WHEEL.

58,164.

Specification for Design. **Patented June 14, 1921.**

Application filed March 25, 1921. Serial No. 455,637. Term of patent 14 years.

To all whom it may concern:

Be it known that I, ARTHUR M. STANLEY, a citizen of the United States, residing at Lynn, in the county of Essex and Commonwealth of Massachusetts, have invented a new, original, and ornamental Design for a Vehicle-Wheel, reference being had to the accompanying drawing, forming a part thereof.

The figure is a perspective view of a vehicle wheel showing my new design, which is characterized by tapered rounded spokes radiating toward the rim from opposite ends of the hub.

I claim:

The ornamental design for a vehicle wheel as shown and described.

ARTHUR M. STANLEY.
